Frank Neal Beazle INVENTOR

By
Howard Rose ATTORNEYS.

UNITED STATES PATENT OFFICE.

FRANK NEAL BEAZLE, OF PITTSBURG, PENNSYLVANIA.

STEEL-INGOT MOLD.

SPECIFICATION forming part of Letters Patent No. 290,626, dated December 18, 1883.

Application filed April 7, 1883. (No model.)

To all whom it may concern:

Be it known that I, FRANK NEAL BEAZLE, a resident of Pittsburgh, in the county of Allegheny and State of Pennsylvania, have invented 5 certain new and useful Improvements in Steel-Ingots Molds; and I do hereby declare that the following is a full, clear, and exact description of the invention, which will enable others skilled in the art to which it appertains 10 to make and use the same, reference being had to the accompanying drawings, and to letters of reference marked thereon, which form a part of this specification.

My invention relates to molds used in casting steel into ingots; and it consists, particularly, in an improved bottom therefor, which I have hereinafter described and specifically claimed.

In the drawings, Figure 1 is an inside view, 20 and Fig. 2 an outside view, of my improved mold. Figs. 3 and 4 show the form in general use. Fig. 5 is the removable end piece or bottom; Fig. 6, a top view of the mold. Fig. 7 shows a modification in construction of the bottom.

Like letters of reference refer to like parts. The letters A A' represent the two sections of the mold, held together by slip-bands C C', and having an eight-sided bore, G, extending 30 lengthwise through the center to form the ingot.

B is a cylindrical piece of metal shaped in the manner of a tapering plug, having two flat faces, b b. This plug fits into a cylindrical bore, F, in the end of the mold, the bore being made about three-fourths of an inch larger than the bore in the mold for casting the ingots, so that a shoulder, e, will be formed in 35 the wall of the mold as a stop for the end of the plug, which forms a closed end or bottom for the mold. This end piece is made to fit neatly into the recess provided for it, the lower end projecting slightly below the end of the mold, so that the weight of the mold will bear 40 directly on it when standing upright, for the purpose of holding it in its place, by resting the mold upon it during the process of casting the ingots.

The mode of operation is to first clamp the 50 two sections of the mold together by slipping

the bands over the outside of the mold. The mold is then placed upright, with the lower end resting on the end piece. The operator then pours in the molten metal until the mold is full. When the metal is sufficiently cool, 5 the clamps are removed from the body of the mold and the ingot taken out.

The removable end piece can be made eight-sided, similar to the bore in the mold; or it can have any other number of sides, it being essential in all cases that the bottom piece be somewhat larger than the bore in the mold for casting the ingot, so there will be no joint in the line of the falling metal. I find the cylindrical-shaped bottom piece to possess the advantage of being placed more readily into the bore or recess in the bottom of the mold.

In the casting of metals, where it is desirable that a different material should be brought in contact with the molten metal than that of which the mold is made—such as fire-clay or carbonaceous materials of any kind—I make a recess in the upper face of the bottom piece (shown at c in Fig. 7) and fill it in with the desired material. By making the recess larger 75 in the bottom than at the top, it operates to hold the substance firmly in place. Small holes can also be bored in the bottom of the recess in different directions for the same purpose.

Carbonaceous materials or clays of any kind can readily be placed in the end of the mold, by means of the recess in the bottom piece, if such is found desirable in the process of casting the various metals.

Having described my invention, what I claim, and desire to secure by Letters Patent of the United States, is—

The combination, with a sectional mold for casting metal into ingots, of a plug of larger 90 diameter than the bore of the mold, and fitting in a recess in the end of the said mold to form the bottom, substantially as described.

In testimony that I claim the foregoing as my own I hereto affix my signature in presence of 95 two witnesses.

FRANK NEAL BEAZLE.

Witnesses:

EPH. SMITH,
JOHN PRENTICE.
